UNITED STATES PATENT OFFICE.

HENRY W. MERRITT, OF SYRACUSE, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 918,576.

Specification of Letters Patent. Patented April 20, 1909.

Application filed June 30, 1905. Serial No. 267,812.

To all whom it may concern:

Be it known that I, HENRY W. MERRITT, citizen of the United States, and resident of Syracuse, in the county of Onondaga and State of New York, have invented certain new and useful Improvements in Type-Writing Machines, of which the following is a specification.

My invention relates to typewriting machines and more especially to tabulating mechanism for such machines.

My invention has for its principal object to provide an improved denominational tabulator.

My invention consists in certain features of construction and combinations and arrangements of parts which will be fully set forth herein and particularly pointed out in the claims.

In the accompanying drawings, Figure 1 is a side elevation of a typewriting machine having my invention applied thereto, the main frame being shown in section just inside of the right-hand side plate. Fig. 2 is a top plan view, most of the upper part of the typewriter mechanism being broken away. Fig. 3 is a rear elevation, the base of the machine being shown in section on the line x x of Fig. 1. Fig. 4 is a diagrammatic enlarged end view of the drum that carries the denomination stops. Fig. 5 is a diagrammatic view showing a development of the interior of said drum.

In most of the views parts have been omitted or broken away or shown in section as has been found convenient.

I have shown my invention applied to the Monarch front-strike typewriter, but it will be obvious that said invention may be adapted to other styles of typewriting machines.

The main frame of the machine shown in the drawings comprises a base portion 1 from which rise posts 2 that support a top plate 3. Two posts 4, rising from said top plate, support stationary rails 5 which are grooved to coöperate with anti-friction balls or rollers 6, which support a carriage 7 by means of grooved rails 8 forming part of said carriage. A platen 9 is mounted in said carriage. The carriage is drawn across the machine by a spring drum 10 acting through a strap 11 which is connected at one end to said drum and at the other end to the carriage. A feed rack 12 is mounted on arms 13 that are pivoted at 14 to the carriage. Said

feed rack is pressed by springs 15 into engagement with a feed pinion 16 which is mounted on the forward end of a shaft 17 which is journaled in a bracket or housing 18 mounted on the top plate 3. At its rear end 60 the shaft 17 carries an escapement wheel 19 which is controlled by feed dogs 20 mounted on an arm 21 that rises from a horizontal rock shaft 22 that is pivoted on pivot pins 23 mounted in a bracket 24 that depends from the top plate 3. The arm 21 and rock shaft 22 form parts of a dog rocker which also has a forwardly extending arm 25 having at its end laterally spreading arms 26 which are connected by links 27 to a universal bar 28, which lies beneath a series of key levers 29. The key levers 29 are pivoted at 30 and at their forward ends carry character keys 31. Each of said key levers has pivoted thereto a sub-lever 32 which is connected by 75 a link 33 with one of a series of type bars 34 which are pivotally mounted in a type bar segment 35. The parts above referred to are of known construction, and so far as my invention is concerned they may be of any 80 suitable construction. The main frame of the machine also comprises a cross-bar 36 which joins the two side plates of the base portion of the machine just back of the keyboard and above the key levers and a second cross-bar 37 which joins said side plates near the middle of the machine. 85

My tabulator mechanism comprises a series of key levers which are mounted in a frame detachably secured to the cross bars 36 and 37 above the key levers 29 and below the type bars 34. Said frame comprises a front bar 38 which lies on the cross bar 36 and two side bars 40 which extend toward the rear of the machine from said front bar. Said front bar is secured to the frame bar 36 by screws 41. The key levers 42 are pivoted at their rear ends on a rod 43 which is mounted at its ends in two brackets 44 which rise from the side bars 40 of the key lever frame. Said rod passes through openings in said brackets and is secured in place by set screws 45 which are threaded through the brackets and engage the rod. Near their forward ends the key levers 42 pass through a slotted plate 46 which is secured to the frame bar 36 by screws 47. The key levers 42 carry tabulator keys 48 on the forward ends, said keys being arranged in a row back of and above the character keys 31. The downward motion of 105 110

said key levers is limited by the lower ends of the slots in the plate 46. Said key levers are returned to normal position by springs 49 which are secured at their rear ends to a plate 50 which is secured to the cross bar 37 by screws 51. The forward ends of the springs 49 press upward on pins 52 projecting from the sides of the key levers 42. The plate 50 is slotted and constitutes a comb plate to 10 guide the rear ends of the key levers 42.

The several keys 48 are adapted to move a rocking frame different distances in order to set the tabulator stops to arrest the carriage in different positions. Said rocking frame 15 comprises a rock shaft 53 pivoted on the reduced ends of pivot screws 54 which are threaded through ears 55 depending from the side bars 40, just back of the frame bar 36. The pivot screws 54 are provided with 20 lock nuts 56. Arms 57 and 58, projecting toward the back of the machine from the rock shaft 53, are connected together by a cross bar 59 which lies beneath the key levers 42. Said cross bar 59 is obliquely disposed 25 beneath the key levers so that one end thereof is much nearer to the pivot rod 43, on which the key levers are pivoted, than the other end and also farther from the pivotal axis of the frame itself. Adjustable contact 30 screws 60 are threaded through the bar 59, one beneath each of the key levers, and in position to be engaged by said key levers when the latter are depressed. The relation 35 between any key lever and the rock frame 35 may be regulated by adjusting the appropriate screw 60.

An arm 61 projects from the rock shaft 53 toward the back of the machine, its rear end lying beneath the frame bar 37. For the 40 sake of rigidity, the arm 61 is connected to the arm 58 and bar 59 by a bracket 61^a. The free end of said arm 61 has pivoted thereto at 62 the lower end of a link 63 which extends upward and toward the rear of the machine 45 through a suitable opening in the cross bar 37 and through a suitable opening in the top plate 3. The upper end of said link 63 is pivoted by a shouldered and headed screw 64 to a segmental rack 65 which is journaled on 50 a shouldered and headed screw 66, which is threaded into a flat portion 67 of one of the posts 4 that support the stationary rails for the carriage. The link 63 consists of two parts which are connected together by a turnbuckle 68 by adjusting which the length of the link may be varied. A returning spring 69 is coiled about the link 63 and is compressed between the upper surface of the frame bar 37 and a washer 70 which surrounds the link 63 and lies against the turnbuckle 68. The rack 65 meshes with a pinion 71 rigidly mounted on one end of a tabulator bar 72 which is rotatably mounted in brackets 73 which project toward the rear of the 65 machine from the posts 4. At the end of the

tabulator bar, opposite the pinion 71, said tabulator bar is journaled in a sleeve 74 which is threaded through the bracket 73 and is adjustable therein, so as to regulate the position of the tabulator bar width-wise of 70 the machine. Said tabulator bar is formed on its front and rear sides with slots 75 spaced a letter space distance apart, and tabulator stop pieces 76 are adapted to be mounted on said tabulator bar and positioned by said 75 slots. Said stop pieces have the form shown in Fig. 4, that is to say, they are U-shaped and are adapted to straddle the bar 72, entering the slots 75. Each of said stop pieces has projecting therefrom a lug or arm 77 which 80 constitutes a column stop.

The denomination stops consist of a series of lugs 78 projecting inward from the inner surface of a cylindrical drum or barrel 79 which, as best shown in Fig. 2, is mounted on an arm 85 or bracket 80 projecting toward the rear of the machine from the carriage 7 to which it is secured by screws 81 (Fig. 3). The drum 79 surrounds the tabulator bar 72 and is concentric therewith. The denomination stops 90 78 are spirally arranged within said drum, said stops being spaced a letter space distance apart along the axis of the drum, and being uniformly spaced around the drum, except that in the space normally occupied 95 by the column stop 77 there is no denomination stop 78. In the normal position of the parts shown in Fig. 4 the drum 79 is free to travel back and forth with the carriage without striking any of the column stops, but if 100 the bar 72 be turned out of its normal position it will bring the column stops 77 into the path of one or another of the denomination stops and said column stop will be in position to arrest the carriage in a column the position of which is determined by the position of the column stop on the bar 72 and at a denominational position within said column determined by the extent to which said bar has been rotated away from its normal position. 110 When any tabulator key is depressed the key lever 42 engaging its screw 60 will depress the frame bar 59 and rock the shaft 53 through a distance depending upon the key depressed. The motion of the rock shaft 53 115 will be communicated through the arm 61, link 63, segment 65, and pinion 71 to the tabulator bar 72 and will bring the tabulator stops 77 into the path of that one of the denomination stops 78 which corresponds to 120 the key depressed.

In order to release the carriage by the depression of any of the tabulator keys, each of the key levers 42 is prolonged so as to extend back of the pivot 43 and a universal bar 125 82 is provided, said universal bar lying across the rear ends of all of the key levers. The universal bar 82 is carried by arms 83 projecting from a rock shaft 84 which lies above the pivot rod 43 and is pivoted on pivot pins 130

85 which project through holes in the brackets 44 and are secured in position by set screws 86. Each of the key levers 42 has an adjusting screw 87 threaded through its rear 5 end and it is the end of this screw that contacts with the universal bar when the key is depressed. The relation of each key to the universal bar may be regulated by adjusting the screw 87. An arm 88 projects toward 10 the rear of the machine from the rock shaft 84 and said arm has pivoted to its rear end at 89 an upwardly extending link 90 which is connected at 91 to a rack lifter 92 which extends upward through an opening 93 (Fig. 2). 15 in the top plate 3. The upper end of the rack lifter 92 is forked, as shown in Fig. 3, to straddle the reduced forward end of the housing 18 in which the escapement wheel shaft 17 is journaled. Each of the forks of the 20 rack lifter is bent toward the front of the machine, as shown in Fig. 1, and lies beneath the feed rack 12. The construction is such that when any tabulator key is depressed the universal bar 82 is elevated and the arm 88 25 through the link 90 elevates the rack lifter, which raises the feed rack 12 out of engagement with the pinion 16, thus releasing the carriage from its escapement devices. At the same time the tabulator bar 72 is rotated 30 by the key to bring the column stop 77 into the path of the selected denomination stop 78.

Various changes may be made in the details of construction and arrangements without departing from my invention.

35 What I claim as new and desire to secure by Letters Patent, is:—

1. In a typewriting machine and tabulating mechanism, the combination of a carriage; a series of character key levers; printing instrumentalities operated by said key levers; a column stop, and a segmentally arranged series of denomination stops; a rock shaft adapted to effect a relative rotation of 40 said column stop and said series of denomination stops to bring said column stop and any selected one of said denomination stops into coöperative position; a pinion on said rock shaft; a segmental rack meshing with said pinion; a series of tabulator keys pivoted near their rear ends and arranged above said 45 series of character keys; a rock frame pivoted near its forward end beneath said series of tabulator keys and comprising a yoke-bar obliquely arranged beneath said series of 50 tabulator keys, whereby said rock frame will be moved different distances by the different keys; and a link connecting said rock frame with said segmental rack.

2. In a typewriting machine and tabulating mechanism, the combination of a carriage; a series of character key levers; printing instrumentalities operated by said key levers; a cylindrical drum mounted on 55 said carriage and having a spirally arranged series of denomination stops projecting from

its inner surface; a rock shaft mounted on the frame of the machine and extending through said drum; one or more column stops mounted on said rock shaft and adjustable longitudinally thereof; a pinion on 70 said rock shaft; a segmental rack meshing with said pinion; a series of tabulator key levers mounted above said series of character keys; a universal frame mounted beneath said series of tabulator key levers; and 75 a link connecting said universal frame with said segmental rack.

3. In a typewriting machine and tabulating mechanism, the combination of a carriage; a series of character keys; printing instrumentalities operated by said character keys; a frame detachably mounted on the main frame above said series of character keys; a series of tabulator key levers pivoted 80 in said frame and having keys in the keyboard of the machine; a rock frame mounted in the first mentioned frame beneath said tabulator key levers; adjustable contact pieces mounted in said rock frame, one beneath each of said tabulator key levers, said 85 contact pieces being at different distances from the pivots of the different levers; a column stop and a series of denomination stops for said carriage mounted for relative adjustment to cause said column stop to coöperate with any one of said denomination stops; and means controlled by said rock 90 frame for effecting such relative adjustment.

4. In a typewriting machine and tabulating mechanism, the combination of a carriage; a series of character key levers and printing instrumentalities operated thereby; a stationary frame mounted on the main frame of the machine above said series of character key levers; a series of denominational tabulator key levers mounted in said frame and having keys arranged in a tier back of the character keys; a universal rock frame pivotally mounted in said stationary frame and adapted to be engaged by said tabulator key levers at different distances from the pivots of said key levers; a universal bar mounted in said stationary frame and lying over the rear ends of said tabulator key levers; denominational stop mechanism controlled by said rock frame; and carriage release mechanism controlled by said universal bar.

5. In a typewriting machine and tabulating mechanism, the combination of a carriage; a stationary frame mounted on the main frame and comprising a transverse pivot rod 43; a series of tabulator key levers of equal length mounted on said pivot rod and extending to the keyboard of the machine; keys mounted on said tabulator key levers and arranged in a tier at the rear of the character keys; a rock frame pivoted in said stationary frame forwardly of the pivot rod 43 and comprising a cross bar 59 lying 120

- beneath said tabulator key levers obliquely so that said key levers engage said bar at different distances from the pivotal axis of said rock frame; a universal bar 82 pivoted in said stationary frame and lying above said tabulator key levers back of the pivot rod 43, denominational carriage stop devices controlled by said rock frame; and a carriage release device controlled by said universal bar.
- 6: In a typewriting machine and tabulating mechanism, the combination of a carriage; a series of character key levers; a series of front-strike type bars operated by said character key levers; a stationary frame mounted on the main frame above said series of character key levers and beneath said series of front-strike type bars; a series of tabulator keys of equal length pivoted in said stationary frame and having 20 keys thereon arranged in a tier back of the character keys; a rock frame pivoted in said stationary frame and having a cross bar 59 lying obliquely beneath said series of tabulator keys so that said keys engage said cross 25 bar at different distances from their pivots; a universal bar lying over said tabulator keys back of their pivots; denominational carriage stop mechanism controlled by said frame; and a carriage release device controlled by said universal bar.
- 10 15 20 25 30

Signed at Syracuse, in the county of Onondaga and State of New York, this 23d day of June, A. D. 1905.
